DESIGN FOR A SALT AND PEPPER SHAKER OR SIMILAR ARTICLE

Yukio Buma, New York, N. Y., assignor to Morimura Bros. Inc., New York, N. Y., a corporation of Japan

Application December 10, 1936, Serial No. 66,440

Term of patent 7 years

To all whom it may concern:

Be it known that I, Yukio Buma, a subject of the Emperor of Japan and a resident of the city, county, and State of New York, have invented a new, original, and ornamental Design for a Salt and Pepper Shaker or Similar Article, of which the following is a specification, reference being had to the accompanying drawing, forming part thereof.

In the drawing,
Figure 1 is a plan view of a salt and pepper shaker, showing my new design, and Figure 2 is an elevation thereof.

I claim:

The ornamental design for a salt and pepper shaker or similar article, as shown.

YUKIO BUMA.
